UNITED STATES PATENT OFFICE.

ARTURO CIANO, OF ROME, ITALY.

HAND-THROWN BOMB.

Application filed September 5, 1923. Serial No. 660,979.

To all whom it may concern:

Be it known that I, ARTURO CIANO, marine officer, late of the Royal Italian Navy, a subject of the King of Italy, residing at Rome, in the Kingdom of Italy, have invented certain new and useful Improvements in Hand-Thrown Bombs, of which the following is a specification.

This invention relates to and comprises improvements in hand thrown bombs, the object of said improvements being to render the bomb absolutely safe while being handled or transported and at the same time to ensure that it will explode even when striking against soft materials.

The invention consists more especially in improvements in the type of bomb comprising three safety devices which act successively, the first of which may be removed by hand after having cocked the striker, the second, upon the bomb having been thrown, is eliminated automatically during the travel of the same upon a portion of the trajectory and the third one allows the striker to work only when the bomb strikes the object.

In the annexed drawing schematically illustrating a practical form of embodiment of the invention:

Figure 1 shows a vertical section of the bomb.

Figure 2 is a front view of the upper portion of the bomb.

Figure 3 is a cross-section of Figure 1.

Figure 4 is a view of the complete bomb, the view being orthogonal relatively to Figure 2.

Figure 5 shows a detail.

As it is shown in the drawings the bomb is made of a shell 1, preferably water-tight, of metal plate or other suitable material, provided on its upper end with a filling hole 26 and with another hole closed with a plug 2.

Inside the shell the cavity 3 is designed to receive the percussion device, and the cavity 4 is designed to receive the locking device as well as the third safety device forming a portion of the locking device itself. The percussion device comprises a striker 5 with a stem 5 and a guiding head 6, a firing pin 7, a cocking spring 8 and a percussion-cap 10. In the embodiment shown the stem 5 is connected with the guiding head 6 by means of the pin 33 the pin 7 is fastened to the head of the striker and the percussion-

cap 10 is placed in the plug 9 below the pin and communicating with the detonator 11.

The locking device is formed of a trip lever, pivoted at 12, which by spring 25 is kept with its end 13 pressed against the sloping face 14 of the head 6 of the striker and with the other arm 15, whose extremity is shaped like a cheek with a spherical recess 17, bears upon the ball 16. The lever is kept locked in its normal position owing to the same bearing upon the ball which prevents the right arm from turning upwards, and through the thrust of spring 25 which prevents the left arm from turning up, keeping it pressed against the end of the striker.

The ball 16 is held in place by the spherical recess 17, by a cheek 18 provided on the upper head 19 of the bomb, and by the spherical recess of the cheek 21 fixed upon a shoulder 22 which is integral with the safety metal plate 20; the latter forming a second safety device arranged between the lower edge 24 of head 6 and the cap-holder 10.

The upper portion of the stem 5 of the striker is provided with a slot 23 within which is lodged a tooth 28 of a plate 27 (Figure 5). The plate 27, which constitutes the first safety device, is connected to a cotter 29 by means of the ring 32 said cotter in turn being connected with a heavy plate 30 which is held in place by a ribbon 31 wound upon the bomb. When the striker is uncocked the tooth 28 is held within the slot 23 by means of the plug 2, but upon cocking the striker said tooth 28 may be freely withdrawn from the slot 23.

The shoulder 22 is connected by means of a ribbon 31 which is wound upon the lateral surface of the bomb head with the heavy plate aforesaid, the latter being by means of the cotter 29, connected as stated, to the safety metal plate 27 forming the first safety device.

The shoulder 22 is connected also to the surface of the bomb by means of a flexible tie, a ribbon or string, not shown in the drawing.

The above described system works in the following manner.

Before throwing the bomb the end of the stem 5 of the striker is partially pulled out from its lodging, until the end 13 of the releasing lever sliding along the side of the head 6 is caused to automatically bear against and below the edge 24 of said

head; in this way the striker remains cocked up.

After the striker has been cocked, the plate 27 is drawn out, which forms the 5 first safety device, by pulling out the tooth 28 from slot 23 and in this way is withdrawn also the cotter 29 which retains the plate 30.

Upon throwing the bomb, the plate 30, which is no longer retained by the cotter, 10 acting on account of its own weight unwinds the ribbon 31 wound upon the bomb, whereupon drops down together with the plate 30, the ribbon 31, the shoulder 22, the stop cheek 21 fixed to the shoulder 22 and the 15 safety plate 20 (forming the second safety device) which is integral with the shoulder.

After the removal of the shoulder 22, and the parts connected therewith the ball 16 is kept in its place only by the cheeks 20 17 and 18 and through the action of the radial pressure exerted by the cheek 17 at the end of lever 4.

It is to be noticed that the vertical diameter of the ball 6 passes somewhat inward 25 the right hand edge of the bearing surface of the cheek 17; besides the length of the arms of the lever 4 is such that the radial pressure on the bearing points of the ball is much less than the tension of spring 3 of 30 the striker.

When in the above conditions of equilibrium of the ball the projectile strikes, no matter how slightly against anything, the ball, by effect of inertia, shifts laterally. 35 The end 17 of the lever 4 may then freely

turn upward and the striker by being released may strike against the percussion-cap.

It should be noted that the system constituted by the parts 30, 31, 21, 20 unwinds 40 upon throwing the bomb but remains connected to the bomb and acts as a flexible rudder whilst the bomb travels along the descending branch of the trajectory. The length and weight of the steering device are 45 such as to keep the bomb steered and to cause it to strike the ground in the best position for the operation of the ball.

I claim as my invention:

In a hand-thrown bomb equipped with 50 successively acting safety devices contained in the head of the bomb, the combination with the locking lever, of a ball being engaged by a spherical recess formed on the arm of said locking lever and constituting the last 55 safety device, a cheek provided in the head of the bomb in engagement with the said ball, and a shoulder in the head of the bomb formed also with a cheek bearing against the said ball, the said shoulder being a portion 60 of the previously acting safety device automatically eliminated during the travel of the bomb.

In testimony whereof I affix my signature in the presence of two subscribing 65 witnesses, this 20th day of August, 1923.

ARTURO CIANO.
